UNITED STATES PATENT OFFICE.

GEORGE WESTINGHOUSE, OF PITTSBURG, PENNSYLVANIA.

DRAW-GEAR AND BUFFING APPARATUS.

SPECIFICATION forming part of Letters Patent No. 672,117, dated April 16, 1901.

Application filed September 27, 1900. Serial No. 31,288. (No model.)

To all whom it may concern:

Be it known that I, GEORGE WESTINGHOUSE, of Pittsburgh, in the county of Allegheny and State of Pennsylvania, have invented a certain new and useful Improvement in Draw-Gear and Buffing Apparatus, of which improvement the following is a specification.

My present invention is an improvement upon certain features of structural embodiment of that for which Letters Patent of the United States No. 649,187 were granted and issued to me under date of May 8, 1900; and its object is to provide a draw-gear and buffing apparatus of the general class or type set forth in said application, in which a simple, compact, and effective hydraulic-pressure apparatus shall be employed as the secondary resistance element and in which waste by leakage of the liquid employed shall be effectively prevented.

The improvement claimed is hereinafter fully set forth.

In the accompanying drawings, Figure 1 is a vertical longitudinal central section through a draft and buffing apparatus embodying my invention; Fig. 2, an inverted plan view of the same; and Fig. 3, a vertical transverse section, the right-hand half of which is taken on the line *a a* of Fig. 1 and the left-hand half on the line *b b* of the same figure.

As in my Letters Patent No. 649,187 aforesaid the apparatus of my present invention embodies a preliminary resistance element, and a secondary or final resistance element which is adapted to exert its action independently of and supplementally to that of the preliminary resistance element. The secondary resistance element is, further, in the form of a hydraulic pressure mechanism, as hereinafter fully and at length described.

In the practice of my invention each of the draw-bars 1 is provided with a suitable coupling-head, which is not shown, and is fitted to move longitudinally within a short range of traverse below the center sills 5 of the car. The outer ends of the draw-bars and the connected coupling-heads project beyond the end sills of the car in the ordinary manner.

Tractive force and strains of draft and buffing applied to either of the draw-bars 1 are transmitted therefrom to the car-frame

through a resistance mechanism which is supported by a horizontal frame-plate 3, of cast or wrought metal, secured by bolts or rivets 55 to the lower sides of the center sills 5. A draw-bar stop or abutment 3^a projects downwardly from and is suitably secured to the frame-plate 3, being in this instance shown as cast integral therewith, and open-ended 60 pressure-cylinders 24 24^a are cast integral with or otherwise fixed to the draw-bar stop 3^a, said pressure-cylinders projecting from the front and rear sides, respectively, of the draw-bar stop in or substantially in line axially with the draw-bar. A draft-spring 12^a abuts against the rear side of the draw-bar stop 3^a and against a piston 23^a, and a buffing-spring 12 abuts against the front side of the draw-bar stop and against a piston 23. Each 70 of the pistons 23 23^a is fixed to and closes the outer end of one of the halves or sections of a transversely-divided cylinder 23^b, the two sections of the cylinder abutting and forming a tight joint at their adjacent ends and being 75 secured firmly together by longitudinal bolts 23^d. The cylinder-sections 23^b are bored to fit truly around and traverse longitudinally on the peripheries of the pressure-cylinders 24-24^a, on which the connected pistons and 80 cylinders are adapted to move as a unit in accordance with the inward and outward movements of the draw-bar 1, to which they are coupled by a pin or bolt 19^d, passing through draw-bar straps or lugs 19, secured 85 to the inner end of the draw-bar, and through an eye or socket 23^c, projecting from the outer face of the adjacent piston 23. The cylinder-sections 23^b are open at top around and at some distance from the draw-bar 90 stop 3^a in front and rear thereto, and their walls, which surround the upper opening thus provided, are upwardly extended to form a liquid-reservoir 25, which is covered by removable caps 25^a, below which the adjacent faces of the walls of the reservoir are adapted to traverse freely. An opening closed by a removable plug may be formed in one or the other of the caps to admit of the supply of liquid to the cylinders.

It will be seen that the connected cylinder-sections 23^b 23^b and outer end pistons 23 23^a constitute a closed-ended cylinder, which is movable in either direction with the draw-

- bar 1 and which is open only to the superposed liquid-reservoir 25, and that the draw-bar stop 3^a not only performs the function of an abutment through which strains applied 5 to the draw-bar are transferred to the car-frame, but also acts as a fixed piston or abutment relatively to the movable cylinder in the institution of the secondary hydraulic resistance to strain on the draw-bar.
- 10 A final release - port 28 of comparatively small transverse section, which is always open, is formed in the upper portion of the wall of each of the pressure-cylinders 24 24^a adjacent to the draw-bar stop 3^a, said final release- 15 ports establishing continuous communication between the cylinders 24 24^a and the liquid-reservoir 25. A preliminary release-port 32, of sufficient capacity to permit of the free discharge of liquid from the cylinder to the 20 reservoir without substantial resistance to the movement of a piston acting on liquid in the cylinder, is also formed in the upper portion of the wall of each of the cylinders 24 24^a. The preliminary release-ports 32 are located 25 in such position on the cylinders 24 24^a that in the normal position of the parts—that is to say, when the draw-bar is not subjected to strain—both of said ports will be fully open and establish free communication between the 30 cylinders in which they are respectively located and the superposed liquid-reservoir; but one or the other of said ports will be closed by the wall of the adjacent cylinder-section 23^b after the draw-bar has under the action 35 of applied strain traversed a determined distance inwardly or outwardly, as the case may be. A single release-port in each cylinder of differential transverse areas—that is to say, progressively diminishing in transverse area 40 from its outer to its inner end—would constitute a mechanical equivalent for the preliminary and final release-ports described and shown and may if desired be substituted therefor without departing from the operative principle 45 or essential features of my invention.
- In the operation of an apparatus embodying my invention the pressure-cylinders 24 24^a, the spaces between the outer ends thereof, and the pistons 23 23^a and the liquid-reservoir 50 25 having been supplied with oil, water, or other incompressible liquid, preliminary strains and those which are of comparatively minor force and extent are opposed and counteracted, either in draft or in buffing, by the 55 draft-spring 12^a or the buffing-spring 12, as the case may be, such strains and all other strains to which the apparatus is subjected in service acting initially upon one or the other of said springs, and their resultants being 60 transmitted to the car-frame through the draw-bar stop 3^a. During the traverse in either direction of the draw-bar and the connected cylinder 23^b and pistons 23 23^a throughout the whole or any portion of a range corresponding 65 with the maximum resistance to compression of the draft or the buffing-spring liquid will pass freely from the cylinder con-

taining the spring which is acted on to the liquid-reservoir through the release-ports 28 and 32, and no hydraulic resistance will be 70 exerted in opposition to the applied strain. Upon the application of strain to the draw-bar which exceeds the maximum capacity of resistance of either of the springs the corresponding preliminary release-port 32 will be 75 closed by the adjacent cylinder-section 23^b in and by the further traverse of the draw-bar and pressure will be exerted upon the liquid in the pressure-cylinder 24 or 24^a, as the case may be, against the resistance of 80 said liquid in being compelled to pass to the reservoir 25 through the restricted final release-port 28. The resistance of the liquid will be proportionate to the strain exerted on the draw-bar and the sectional area of the 85 final release-passage, and the imposed final strain will be opposed and counteracted by such hydraulic resistance. Upon the release or cessation of strain upon the draw-bar the parts will be returned to normal position by 90 the spring which has been initially compressed, and the liquid which was expelled from the inclosing pressure-cylinder will be returned thereto through its release-ports.

It will be seen that the relation of the pressure-cylinders 24 24^a and the inclosing cylinder 23^b and pistons 23 23^a is such that during the exertion of pressure upon the liquid in one of the pressure-cylinders that in the other pressure - cylinder is wholly exempt 95 from pressure, and also that no stuffing-boxes or analogous devices for the prevention of leakage are required, inasmuch as the opening in the liquid-reservoir is the only passage to the interior of the cylinder through 100 which relative traverse of the piston and cylinder is effected and permitted. The opening of the liquid-reservoir being in a horizontal plane and the reservoir being above the level of the pressure-cylinders and not subjected at any time to pressure there is no 105 tendency to waste or leakage of liquid from the reservoir, and the return of liquid therefrom to each of the pressure-cylinders is effected wholly by gravity and without involving 110 the employment of valves of any description.

It will also be seen that a leading and essential feature of my present invention consists in combining with a draw-bar a piston or abutment and a cylinder, one of which is movable by connection with the draw-bar relatively to the other in order to induce the exertion of resistance by an interposed body of liquid to the movements of the draw-bar and a liquid-reservoir having an opening above the upper 120 level of the cylinder and unsubjected to pressure, whereby traverse of the movable member may be effected without leakage of liquid. In the preferred form of my invention herein set forth a fixed piston or abutment and a 125 relatively movable cylinder are employed; but it will be obvious to those skilled in the art that the relation of the cylinder and pis-

- ton may, if desired, be reversed—that is to say, the cylinder may be fixed and the piston or abutment be connected to and movable with the draw-bar—without departure from the spirit and operative principle of my invention. Such relative disposition of these members I therefore specify as the mechanical equivalent of that specifically hereinabove described.
- 10 I claim as my invention and desire to secure by Letters Patent—
1. In a draw-gear or buffing apparatus, the combination of a draw-bar, a piston or abutment and a cylinder, one of which is movable, by connection with the draw-bar, relatively to the other, a liquid - reservoir having an opening above the upper level of the cylinder, through which opening relative traverse of the piston and cylinder is effected and permitted, and a release-port connecting the cylinder and liquid-reservoir.
  2. In a draw-gear or buffing apparatus, the combination of a draw-bar, a piston or abutment and a cylinder, one of which is movable, by connection with the draw-bar, relatively to the other, a spring interposed between and bearing on the piston and cylinder, a liquid-reservoir having an opening above the upper level of the cylinder, through which opening relative traverse of the piston and cylinder is effected and permitted, and a release-port connecting the cylinder and liquid-reservoir.
  3. In a draw-gear or buffing apparatus, the combination of a draw-bar, a draw-bar stop secured to a car-frame and constituting a fixed piston, an open-ended pressure-cylinder fixed to the draw-bar stop, a cylinder connected to and movable with the draw-bar and fitted to traverse on the periphery of the pressure-cylinder, a spring interposed between the draw-bar stop and the opposite head of the movable cylinder, a liquid-reservoir, and a release-port connecting the pressure-cylinder and liquid-reservoir.
  4. In a draw-gear or buffing apparatus, the combination of a draw-bar, a draw-bar stop

secured to a car-frame and constituting a fixed piston, an open-ended pressure-cylinder fixed to the draw-bar stop, a cylinder connected to and movable with the draw-bar and fitted to traverse on the periphery of the pressure-cylinder, a spring interposed between the draw-bar stop and the opposite head of the movable cylinder, a liquid-reservoir, a continuously open final release-port connecting the pressure-cylinder and liquid-reservoir, and a preliminary release-port connecting the pressure-cylinder and liquid-reservoir and controlled by the movable cylinder.

5. In a draw-gear or buffing apparatus, the combination of a draw-bar, a draw-bar stop secured to a car-frame and constituting a fixed piston, two open-ended pressure-cylinders fixed to and projecting oppositely from the draw-bar stop, a cylinder closed at its ends by pistons and connected to and movable with the draw-bar, said cylinder being fitted to traverse on the peripheries of the pressure-cylinders, a draft-spring and a buffing - spring, each interposed between the draw-bar stop and an end piston of the movable cylinder, a liquid-reservoir, and release-ports connecting the pressure-cylinders and liquid-reservoir.

6. In a draw-gear or buffing apparatus, the combination of a supporting-plate adapted to be secured to a car-frame, a draw-bar stop fixed to and projecting downwardly from said plate and constituting a fixed piston, an open-ended pressure-cylinder fixed to the draw-bar stop, a draw-bar, a cylinder connected to and movable with the draw-bar and fitted to traverse on the periphery of the pressure-cylinder, a liquid - reservoir formed by an upward extension of the movable cylinder, and a release-port connecting the pressure-cylinder and liquid-reservoir.
